(57) **CLAIM**

The ornamental design for a roofing shingle, as shown and described.

DESCRIPTION

FIG. 1 is a front, top, left perspective view of a roofing shingle according to a first embodiment showing our new design;

FIG. 2 a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a top, right, rear perspective view thereof;

FIG. 9 is a top, front, left perspective view of a roofing shingle according to a second embodiment showing our new design;

FIG. 10 a front elevation view thereof;

FIG. 11 is a rear elevation view thereof;

FIG. 12 is a top plan view thereof;

FIG. 13 is a bottom plan view thereof;

FIG. 14 is a left side elevation view thereof;

FIG. 15 is a right side elevation view thereof;

FIG. 16 is bottom, rear, right perspective view thereof; and,

FIG. 17 is a bottom, front, left perspective view thereof.

The broken lines in the drawings depict portions of the roofing shingle that form no part of the claimed design.

1 Claim, 13 Drawing Sheets
